UNITED STATES PATENT OFFICE.

WILLIAM C. STEWART, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

OUTSOLE.

1,202,236.

Specification of Letters Patent. Patented Oct. 24, 1916.

Application filed July 1, 1914. Serial No. 848,383.

To all whom it may concern:

Be it known that I, WILLIAM C. STEWART, a subject of the King of Great Britain, residing at Swampscott, in the county of

5 Essex and State of Massachusetts, have invented certain new and useful Improvements in Outsoles; and I do hereby declare the following to be a full, clear, and exact description of the invention, such as will 10 enable others skilled in the art to which it appertains to make and use the same.

This invention relates to soles and more particularly to outsoles for either McKay or Goodyear boots and shoes.

15 In the manufacture of boots and shoes it is desirable that the shank of the outsole be skived, or feather-edged as it is generally termed, on its flesh side to provide room at the breast of the heel for the reception 20 of the forward ends of the counter, and rear beveled ends of the welt in welted shoes, thus enabling these parts to lie in a substantially continuous, unbroken line with the sole after the outsole has been applied 25 to the shoe.

A further feature of advantage resulting from the shank skiving operation is that a light edged shank is produced upon the sole which imparts a better finish to the shoe 30 as a whole.

To gain the full effect of either of the advantages just referred to, care must be taken that the shank skiving operation is properly performed, particularly with relation to the location of the skiving. The skivings should extend forward about to the ends of the ball line on each side of the sole, and rearwardly to a point about opposite the ends of the breast line. At the 40 present time the shank skiving operation is generally performed by the operative passing the sole back and forth past a rotary cutter, the terminal points of the skiving being determined by eye alone. This results in considerable variation in the length 45 of the skived portions of the soles contained in a day's stint and frequently in the lengths and relative locations of the skived portions of the two soles used on the same pair of 50 shoes. As a result the outsoles cannot be

applied to the shoe as nicely as is desired and the appearance of the two shoes of the same pair may be different, a highly undesirable condition.

It is now becoming the practice to mold 55 outsoles for use in Goodyear shoes, especially where "cottage shanks" are desired. The line of the sharp break across the forepart should terminate at the ends of the ball line, that is, just forward of the skived 60 portion of the shank. If the break is not so located relatively to the shank skiving, that is, if it extends forward of the ball line, the molding appears dull and indistinct because the foreparts of the molds of 65 the molding machine are so fitted as to properly take care of a forepart of equal thickness back to the ball line. On the other hand if the shank skiving is not carried far enough forward, that is, to the ball line, 70 the crushing pressure of the sharp angle of the molds is liable to break through the sole or squeeze it out of shape and thus produce a cripple. It is highly desirable, therefore, that not only should the shank skiving be 75 accurately placed on the outsole but that some mark or index be afforded for locating the sole between the molds so that, when molding the sole, the sharp break across the forepart will be properly located relatively 80 to the shank skiving.

The object of the present invention is to fit the outsole, in the process of making it, so that it will be possible for the operative to accurately place the sole on the lower 85 mold of the molding machine with the ball line of the sole on the ball line of the mold, and so that both the forward and rear terminal points of the shank skivings may be accurately determined and thus cause the 90 skived portions on all soles of the same size or style to be located exactly alike.

To the accomplishment of this object the invention comprises the novel sole herein-after described and defined in the appended 95 claims.

In the accompanying drawing, showing the preferred form of the invention, a plan view of the improved sole is illustrated, the curved dotted lines at the margin of the 100

shank indicating the boundary of the cut to be made by the shank skiving knife, and the centrally located dotted lines indicating the sharp break formed in molding a cottage shank.

In the illustrated embodiment of the invention an outsole *a*, which may be a dinked-out sole as shown or may be any other commercial form of outsole, is provided across 10 its lateral edge substantially opposite the ends of the breast line with two gages which are, preferably, shallow notches *b*, and substantially opposite the ends of the ball line with two similar notches *c*. The notches, 15 as will presently be described, determine the terminal points or longitudinal boundaries of the shank skivings, the outlines of which are indicated by the dotted lines *d*.

While the notches for indicating the terminal points of the shank skivings are preferably at the breast and ball lines, for the reason that in the generally accepted method of making shoes a skiving extending between these two lines of the sole is properly located to afford the advantages hereinbefore referred to, the invention does not contemplate that this location of the notches must be rigidly adhered to. In different methods of making shoes, or different styles 30 of shoes, there may be considerable variation in the location of the notches, when used to determine the location of the shank skivings, from what is shown in the drawing.

35 In utilizing the present invention, the shank skiving machine, which may be similar to that disclosed in Letters Patent of the United States to G. L. Preble, No. 693,902, granted February 25, 1902, is provided with a pair of depending, thin gage plates one at the forward side of the rotary knife and one at its rear side. The sole, is, as usual, held in a vertical plane and passed back and forth across the knife in the well 40 known manner, but with its lateral edge in contact with the lower ends of the gage plates. As the sole is reciprocated past and against the knife by the operative the rear gage will, when the greatest desirable forward stroke is made, enter the notch *b* or *c* farthest from the operative, thus indicating to him by sense of touch that no further forward movement should be made, and similarly on the rear stroke of the reciprocations the forward gage will enter the notch *b* or *c* nearest to the operative and indicate to him the rear boundary of the shank cut. As a result a shank skiving is produced in each side of the sole having a 45 length and location in exact accordance with the best practice and desire of the shoe manufacturer.

The forward pair of notches *c*, being in the lateral edge of the sole and therefore 50 visible on viewing the sole edgewise, may

conveniently be used as gages for locating the sole on the lower mold of a sole molding machine in such position that the break in the sole (see dotted lines *g*) resulting from the molding operation, will be produced just at the forward end of the thin or skived portion of the shank. If the step of molding the sole is performed prior to the step of feather-edging the sharp breaks at the edge of the sole at the ends of the ball line form abutments or shoulders which may be used to determine the forward longitudinal boundaries of the skiving cuts.

It will be obvious to those skilled in the art of making shoes that the invention may be successfully carried out by providing the edge of the sole at the desired points with small projections, as indicated by dotted lines at *e* and *f*, instead of notches. In such case the limit of forward and rearward movement of the sole in the shank skiving operation, would be indicated to the operative by the gage plates abutting against the projections. In either manner of preparing the novel sole the gages formed thereon comprise oppositely facing abutments or shoulders which coöperate with the gages of the feather edging machine to determine the length and location of the cut made by the knife of the machine. The sole of the present invention comprises therefore, the addition to the usual sole of conveniently located edge abutments or shoulders, of any suitable character, for use in a subsequent operation on the sole.

It will be understood that after the molding, feather-edging or other subsequent operation has been performed, conveniently during the edge trimming operation on the sole, the gages, whether they be in the form of notches or projections, are removed leaving the desired smooth edge.

The nature and scope of the present invention having been indicated and the preferred embodiment having been specifically described, what is claimed as new is:

1. A sole for boots, shoes and the like, provided at its lateral edge, at points corresponding to the ends of the ball line, with a pair of abutments or shoulders for use as gages in a subsequent operation upon the sole.

2. A sole for boots, shoes and the like, provided at its lateral edge with two oppositely facing abutments or shoulders, one adjacent each end of the shank portion, for use as gages in determining the length and location of a feather edging cut at the shank.

3. A sole for boots, shoes and the like, provided at its lateral edge with two pairs of abutments or shoulders one pair at points approximating the ends of the breast line and the other pair at points approximating the ends of the ball line, for use as gages in determining the length and

location of the feather edging cuts at the two sides of the shank.

4. A sole for boots, shoes and the like, provided at its lateral edge with temporary abutments or shoulders, one adjacent each end of the shank portion of the sole on each side thereof, for coöperating with the gage

of a feather edging machine in determining the length and location of a skiving cut at the shank.
